UNITED STATES PATENT OFFICE.

GEORGE G. BABCOCK, OF PORTLAND, MAINE, ASSIGNEE TO CHARLES T. LIBBY, OF PORTLAND, MAINE.

LINOTYPE-MACHINE.

No. 873,203.

Specification of Letters Patent.

Patented Dec. 10, 1907.

Application filed August 29, 1904. Serial No. 222,656.

To all whom it may concern:

Be it known that I, GEORGE G. BABCOCK, a citizen of the United States, residing at Portland, in the county of Cumberland and 5 State of Maine, have invented certain new and useful Improvements in Linotype-Machines, of which the following is a specification.

This invention relates to improvements in 10 machines of the general character of the so-called Mergenthaler linotype machine Number 436,532, dated September 16, 1890.

In my improved machine the elevator is put up by a weight, spring, or other means 15 which through intermediate connecting mechanism operates when the elevator is free, to put it up, and my invention consists in providing means for effecting an automatic break at some point in the intermediate connecting mechanism, thereby allowing the elevator to fall by gravity, and in 20 means for automatically and periodically restoring the connection.

I will now proceed to describe one specific 25 embodiment of my improvement, reference being had to the accompanying drawing in which

Figure 1 is a perspective view of so much of said linotype machine as is necessary to 30 illustrate the manner in which my improved mechanism is applied thereto, showing a weight to put up the elevator; Fig. 2 is a plan view of the mechanism for making and breaking the connection between the weight 35 and the elevator lever; Fig. 3 is a vertical longitudinal sectional view on line X—X, Fig. 2, the connecting latch and spring being omitted, and Fig. 4 is a detail perspective view of the automatic latch and its sup- 40 port.

Same letters of reference refer to like parts.

In said drawings A represents the elevator, B the vertical guides between which it moves, C portions of the column, D the line 45 delivery carriage shaft, E the line delivery carriage lever, F the lever for raising the elevator rigid on shaft H and G a link connecting the elevator and lever F. These parts are substantially the same and operate in 50 the same way as in said linotype machine.

In the form selected to illustrate my invention a bracket 1 is rigidly secured to some stationary part of the machine in any convenient manner, not shown, said bracket be-

ing provided with an upright bar 2 substantially parallel with link G. Link G is provided on one side with an offset 3 and on the other side with an offset 5. Pivotedly attached to bar 2 is a latch 4 adapted to engage offset 3 when the elevator is down and to be manually disengaged. Pivotedly attached to a plate 6 secured to guides B is a latch 7 adapted to engage offset 5 when the elevator is down and to be automatically disengaged by the return of the line delivery carriage lever. These latches are held in engagement with their respective offsets by springs 8 and 9 respectively and both must be disengaged before the elevator can be sent up.

Secured to shaft H is a lever arm 10 which 70 may be rigid therewith or which may be loosely mounted thereon and provided with a lug 11 projecting into the path of the lever F in which case lever F and with it the elevator is free to be raised independently of arm 75 10. Connecting with the assembling elevator through said lever arm 10, and operated by weight 20 and lug 31 both below mentioned, is a trip-hook mechanism which we now proceed to describe.

Mounted upon bracket 1 is a two part sliding plate, one part 12 connected to lever arm 10 by a pivoted link 13 and the other part 14 pivotally connected to an arm 15 of a bell crank lever pivotally mounted on bracket 1, 85 by means of pivot pin 16 projecting upwardly into a hole 17 in said arm, said hole being somewhat larger than the pin. Attached to said arm by means of a cord 18 passing over pulley 19 is a weight 20 which weight should 90 be sufficient to raise the elevator when free to go up and when the parts 12 and 14 are connected as hereinafter described. The parts 12 and 14 are secured on the bracket and held in alinement therewith by means 95 of screws 33 on the parts of the sliding plate and projecting through slots 34 in the bracket, as shown in Fig. 3.

The parts 12 and 14 of the sliding plate are adapted to be connected and disconnected as hereinafter described, for the purpose, when connected and the elevator is free, of putting up the elevator by means of the weight, and, when disconnected, of permitting the elevator to return down by gravity. For the purpose of detachably connecting the two parts 12 and 14 a latch 21 is pivotally connected to one of the parts of the

sliding plate and a keeper 22 is rigidly secured to the other part of the sliding plate. The latch 21 is adapted to be held yieldingly in engagement with its keeper by means of a spring 23. To disengage the latch a knocker 24 is pivotally secured to a bracket 25 which for convenience is secured to bracket 1. The lower extremity of the knocker may be provided with an adjusting screw 26 which is adapted, when the knocker is turned on its pivot, to strike the arm of the latch and disengage it from its keeper. The pivoted knocker is actuated by means of link 29 pivotally attached to it and to the end of the line delivery carriage shaft by means of which it is operated in time with the movement of said shaft, the rocking movement of the line delivery carriage shaft raising the link 29 and actuating the knocker to throw the latch out of engagement. This is adjusted by means of screw 26 to take place just when the line of matrices has passed out of the elevator, the disengaging of the latch allowing the separation of the two parts 12 and 14 of the plate 25 and thereupon the elevator raising mechanism being free from the influence of the weight, the elevator returns down by gravity until one or both of the latches which hold the elevator down engage their respective offsets, the part 12 of the sliding plate being carried outwardly to the farthest extent. To restore the connection between the two parts 12 and 14, the line delivery carriage shaft which has a rocking motion is provided with a lug 31 which, as the line delivery carriage shaft is rotated, engages arm 30 of the bell crank lever and raises the weight pushing the part 14 forward until latch 21 comes into engagement with keeper 22 again connecting parts 12 and 14, completing the cycle of movement and putting the elevator in readiness to be sent up, whenever it is released. To counterbalance the weight of and to lessen the shock due to the unobstructed fall of the elevator, I employ a spring 32 connecting lever arm 10 and some stationary member as bracket 2.

The operation is as follows. Assume the parts to be in the position shown in Fig. 1 with the elevator down held down by the hand-operated latch, the automatic latch being thrown out by the line delivery carriage lever, and the weight and its connections tending to raise the elevator. The hand-operated latch is then disengaged and the weight, through its connections immediately sends up the elevator. The line delivery carriage shaft turning to the left midway its movement causes through the knocker and intermediate mechanism the disconnection of parts 12 and 14 allowing the elevator to return to its down position by gravity. As the line delivery carriage shaft continues its course lug 31 engages arm 30, raises the weight and again effects the con-

nection of parts 12 and 14. The line delivery carriage shaft has a rocking motion through an angle of about forty-five degrees.

Having thus described my invention and its use, I claim:

1. In a linotype machine, in combination with the vertically movable assembling elevator and mechanically actuated operating devices therefor, a trip hook and block connection between the operating devices and the elevator adapted to stay hooked while pulling the elevator up and unhooked while the elevator returns by gravity. 70
2. In a linotype machine, in combination with the assembling elevator, actuating devices therefor consisting of interlocking trip hook and trip block with connections from the elevator and a source of power, adapted to raise the elevator while interlocked and permit its return by gravity while disengaged. 75
3. In a linotype machine, the assembling elevator adapted to be raised by force and fall by gravity, in combination with a to-and-fro, reciprocating, trip-hook mechanism adapted to automatically effect the former movement and permit the latter movement. 80
4. In a linotype machine, in combination with the vertically movable assembling elevator, trip hook mechanism adapted when connected up to raise said elevator and when disconnected to let it fall, and means for connecting and disconnecting said raising means. 85
5. In a linotype machine, in combination with the assembling elevator, means for raising said elevator comprising component parts connected during their working stroke and disconnected during their return stroke. 90
6. In a linotype machine, in combination with the vertically movable assembling elevator, a trip movement for operating the same adapted to trip at the moment when the matrix line has passed clear of the elevator. 105
7. In a linotype machine, an assembling elevator, elevator raising mechanism comprising a source of power and intermediate connecting mechanism, a make and break connection in said intermediate mechanism, means for automatically making said connection and means for automatically breaking said connection at the moment when the line of matrices has passed out of said elevator. 110
8. In a linotype machine, an assembling elevator, elevator raising mechanism comprising a source of power and intermediate connecting mechanism, said intermediate connecting mechanism being separable and provided one part with a keeper and the other with a pivoted latch adapted to engage said keeper, whereby the connection between the source of power and the elevator may be made or broken and means for operating said latch. 115
- 130.

9. In a linotype machine, an assembling elevator, elevator raising mechanism comprising a source of power and intermediate connecting mechanism between said source of power and elevator, said intermediate connecting mechanism being jointed and provided, one part with a keeper and the other with a pivoted latch adapted to engage said keeper, and a striker operable by a moving part of the machine to disengage said latch at predetermined times and means for effecting reengagement of the latch with its keeper.
10. In a linotype machine, an assembling elevator, elevator raising mechanism, comprising a weight adapted by its fall to raise the elevator, intermediate connecting mechanism between said elevator and said weight, make and break connection in said intermediate connecting mechanism, means for automatically making said connection and means for breaking said connection while the elevator is up.
11. In a linotype machine, the combination with a vertically-movable assembling elevator, of trip-hook mechanism acting automatically by potential, static or stored force for actuating the elevator and means for energizing and controlling said actuating mechanism.
12. In a linotype machine, the combination with a mechanically actuated part thereof and an assembling elevator, of mechanism
- acting by potential, static or stored force for raising the elevator, a trip hook gear adapted to permit the return of the elevator by gravity, and connecting mechanism between said elevator-raising mechanism and said actuated part for energizing said raising mechanism.
13. In a linotype machine, an attachment for operating the assembling elevator adapted to be actuated by potential, static or stored force to raise the elevator and provided with a trip hook gear to permit its return by gravity, the whole operating substantially as described.
14. In a linotype machine, in combination, the reciprocating assembling elevator, a rocking shaft motionless while said elevator goes up and trip-hook mechanism energized from said rocking shaft adapted to actuate said elevator.
15. In a linotype machine, the assembling elevator, the line delivery carriage shaft and trip movement mechanism intermediate said elevator and said shaft adapted to reciprocate the former.

In testimony whereof, I have hereunto affixed my name in the presence of two subscribing witnesses.

GEORGE G. BABCOCK.
